(57) **CLAIM**

The ornamental design for a spill pan, as shown and described.

DESCRIPTION

FIG. 1 is a frontal perspective view of a spill pan according to our new design;

FIG. 2 is a rearward perspective view of the spill pan in FIG. 1;

FIG. 3 is a front view of the spill pan in FIG. 1;

FIG. 4 is a back view of the spill pan in FIG. 1;

FIG. 5 is a right side view of the spill pan in FIG. 1, the left side being a mirror image of the right side;

FIG. 6 is a top view of the spill pan in FIG. 1; and,

FIG. 7 is a bottom view of the spill pan in FIG. 1.

The broken lines immediately adjacent the shaded areas represent the bounds of the claim and all other broken lines are for illustrative purposes only. None of the broken lines and form part of the claimed design.
